(57) **CLAIM**

The ornamental design for a vessel spout as shown and described.

DESCRIPTION

FIG. 1 is a perspective view of a vessel spout comprising a new, original and ornamental design;

FIG. 2 is a front elevational view of the vessel spout shown in FIG. 1;

FIG. 3 is a right side view of the vessel spout shown in FIG. 1;

FIG. 4 is a left side view of the vessel spout shown in FIG. 1;

FIG. 5 is a rear elevational view of the vessel spout shown in FIG. 1;

FIG. 6 is a top plan view of the vessel spout shown in FIG. 1;

FIG. 7 is a bottom plan view of the vessel spout shown in FIG. 1; and,

FIG. 8 is an additional perspective view of the vessel spout shown in FIG. 1.

In FIGS. 1-8, the broken lines depict portions of the article that form no part of the claimed design.
